ERNEST ORÉ, OF CAEN, FRANCE.

REGENERATING COKE-FURNACE.

1,291,621.

Specification of Letters Patent. Patented Jan. 14, 1919.

Application filed October 12, 1917. Serial No. 196,313.

To all whom it may concern:

Be it known that I, ERNEST ORÉ, a citizen of the Republic of France, resident of Caen, (post - office address 11 Rue de la Masse, 5 Caen,) France, have invented a new and useful Improvement in or Relating to Regenerating Coke-Furnaces, which improvement is fully set forth in the following specification.

In regenerating coke furnaces for by-products the heating takes place in heating flues arranged in the vertical partitions, which separate the carbonizing chambers, by the combustion of gases developed in the furnaces themselves or outside, which combustion is effected in air admitted either at the temperature of the surrounding atmosphere or previously heated.

The furnaces are heated satisfactorily only by producing at will in a given zone of the partition the necessary heat, which can be effected only if simple and easy means are available to burn at the said point, the quantity of gas necessary with a suitably regulated amount of air.

The present invention relates to coke furnaces for recovering by-products and for regenerating heat, provided with a horizontal carbonizing chamber, in the partition wall of which there is disposed, throughout its entire length, a series of vertical heating flues which are arranged in such a manner that each one of them can be separately heated to the required temperature by combustion of a suitable quantity of gas mixed with the proper amount of air; this furnace is characterized by multiple heating flues in the form of a reversed U, each heated by a heater which is fed at the desired combustion point, with gas and air supplied in regulated amounts by means of output regulators which are simple and readily accessible.

Figure 1 is an elevation of the front of the furnace, that is to say, of the front seen from the side of the hearth on the lines A 45 B of Figs. 4 and 5.

Fig. 2 is a transverse section of the furnace on the lines C D E F G H of Figs. 4 and 5.

Fig. 3 is a transverse section of the furnace on the lines I J K L M N of Figs. 4 and 5.

Fig. 4 is a longitudinal section through the partition of the front half of the furnace on the line O P of Fig. 3.

Fig. 5 is a longitudinal section of the partition of the furnace on the lines Q R S T of Fig. 2.

Fig. 6 is a longitudinal section through the chamber of the rear half of the furnace on the lines U V X Y of Fig. 2.

Figs. 7 and 8 represent in detail an elevation and a plan view of a burner arranged entirely beneath the partition.

Figs. 9 and 10 represent in detail an elevation and a plan view of a burner, likewise situated under the partition, but fed by gas and air conduits which extend under the hearth of the rear half of the adjoining carbonizing chamber.

The heating arrangement is applied to a furnace heated with admission of combustion air, either of the surrounding temperature or heated in regenerating chambers. In the latter case, owing to the alternative reversal of the draft, the construction of the furnace is more complicated, since a double installation of burners is required for a single partition, whereas but one is required for the other types of furnaces. The following description therefore relates to the more complicated furnace which is provided with regenerating chambers with an intermittent reversal of draft.

In the present arrangement, the furnace has an ordinary carbonizing chamber 1 and an optional number of chambers adjoining each other and separated by partitions 2, constituting a battery. In each partition, and in the walls in the abutments for the end furnaces of the battery, vertical heating flues 3 are separately arranged in the form of a reversed U side by side and in sufficient numbers to occupy the partition or the wall over its whole length, and rising so as to heat the charge in the furnace throughout.

The furnace is provided, as already pointed out, with two groups of burners, alternately ignited and extinguished in turns; the first group is mounted completely under the partition, with its gas and air pipes. The second group likewise burns under the partition, but its gas and air pipes pass and extend under the hearth of the adjoining carbonizing chamber, either at the right or the left, but at the same side, for all the furnaces of the battery. In order to facilitate the description, the burners of the group

mounted entirely under the partition will be called hereinafter partition burners, and those of the other group hearth burners.

In the furnace described for each partition there are sixteen heating flues 3 in the form of a reversed U, each having a partition burner under one branch, and a hearth burner under the other branch; consequently each furnace has sixteen partition burners and sixteen hearth burners which are distributed (for facilitating the construction and the operation) with regard to their air and gas pipes, half at the front and half at the rear of the furnace. Finally, there are eight front partition burners and eight rear hearth burners, and in the same way eight front hearth burners and eight rear partition burners.

With the exception of a few details such as the length and shape of the air and gas pipes, all the burners are of the same type. Taking as example a front partition burner, this consists of a refractory block 4, through which small inlets for the air and gas pass. The gas reaches the burner through a refractory conduit 5 which extends under the partition from the burner to the front of the furnace, where it is connected to a small gas tube 6 provided with an ordinary regulating valve. The eight tubes 6 of the eight front partition burners are branched on an end pipe 7 provided with a regulating valve mounted on a gas conduit 8 which extends in a gallery provided for all the front burners of the battery. For the supply of air refractory conduits 9 are provided in variable numbers for each burner, but limited to two in the example. The said air conduits end in a heated air chamber 10 (they can be arranged at will as far as this point in the same refractory block as the gas conduit). The air chamber 10 communicates through openings 11, regulated by dampers 12, with an intermediate heating flue 13 which is connected, by a flue 14, with a collector 15 connected to a regenerating chamber 16 which is constituted in the ordinary way by a stacking of refractory bricks. (In order to facilitate the description, for each front and rear half of the furnace an independent set of regenerating chambers has been assumed).

As usual, the regenerating chamber 16 is alternately in communication with a blower and flue, the reversal of draft taking place, for instance, every half hour. The conduits 9 therefore serve for the admission of air to the burners during the ignition period of the latter, and for the discharge of the burnt gases during the other period, when the hearth burners are ignited. The conduits 9 are provided, at their ends which enter the air chamber 10, with small refractory dampers 17 which slide in grooves. Opposite to the said dampers the air chamber 10 has in its wall, openings which end

in the gallery and are closed by removable plugs 18. It is enough to remove a plug and to move in the required direction through the opening the small damper 17 by means of a suitable light hook, so as to regulate at 70 will the air admitted at 9. The dampers 12 which control the entrance to the chamber 10 can be operated in the same manner.

The above description will suffice to explain the operation of the heating arrangements. If, for instance, the burners 4 are considered, during their ignition period, the gas supplied through the conduit 5 ignites by contact with the hot air supplied through the conduits 9, at the bottom of the first 80 branch of the flue 3. The products of this combustion rise through the said branch, descend through the other, and come in contact with the hearth burners 19, the gas conduits of which are closed (for this the small 85 gas tubes 20 of each hearth burner have their valves constantly open for the required output; and for the extinction of the burners, closing is effected on the eight burners together with the valve of the end pipe 21, 90 similarly to the end pipe 7 which has been described). The air conduits 22 of the hearth burners, on the contrary, are always open and, at the period under consideration, they serve for the discharge of the products burnt 95 in the burners 4. Without describing the various openings, dampers, etc., which exist under the hearth as well as under the partitions, it will be seen that from the conduits 22 the burnt gases pass to an air chamber 23 100 and, finally, through a collector 24 to a regenerating chamber 25, for the time being in communication with the flue or chimney. The regulation of the small dampers of the conduits 22 is effected by means of a small hook passed through the openings of the air chamber facing the gallery and closed by plugs 26.

When the ignition period of the burners 4 is ended, the draft is reversed in the regenerating chamber, and the regenerating chamber 25 has air blown into it, while the regenerating chamber 16 conveys the burnt gases to the chimney. The gas is turned on to the burners 19 and cut off from the 115 burners 4. It will be seen—and this is very important for the regular operation of regenerating furnaces—that the reversed U tubes constituted by the heating flues are likewise heated in the same way before and 120 after each period of reversal of draft, the only difference being that the heat draft passes through it alternately from left to right, and from right to left, whereby there is absolutely no modification of the heating. 125 The above description regarding the front half of the furnace applies likewise to the rear half, since the two halves are symmetrical relatively to the transverse axis of the furnace. In the same way, the rear 130

partition burners 27 are provided with small gas supplying tubes 28, and an end pipe 29 for the same. 30 is the general conduit for the gas of all the rear burners of the furnace.

31 is the air piping for the burners 27, and 32 indicates the small regulating dampers. Without entering into all the details, 33 is the intermediate flue which communicates with the air chamber 35 (of which 34 are the openings with removable plugs) and also with the collector 36 connected to the regenerating chamber 37 which is coupled with the regenerating chamber 38 for the rear hearth burners, with which it communicates through the collector 39, etc. (A similar arrangement for the rear hearth burners).

On the top of the furnace, openings with removable plugs 40 surmount all the heating flues 3, and enable, when required, the supervision of the combustion. These openings serve also for the subsequent ignition of the burners, more particularly when the combustion air has been admitted at the surrounding temperature.

Claims:

1. In a coke furnace having inverted U-shaped heating flues in the partitions in closing the carbonizing chambers, a burner located at the foot of each branch of each flue and having gas and air openings; a gas supply conduit individual to each burner, a tube leading to each gas conduit and provided with a regulating valve, an end pipe on which said tubes are branched provided with a regulating valve, and a main gas conduit whereon said end pipe is mounted; a plurality of air conduits individual to each burner and leading to the same for supplying heated air thereto, an air chamber from which the air conduits lead, means for

regulating the air supplied by each air conduit, and a collector chamber with which said air chamber is in communication; whereby each flue can be individually heated, independently of the others, to the desired temperature by combustion of gas admitted in the desired quantity and burned with the proper proportion of air.

2. In a coke furnace having inverted U-shaped heating flues in the partitions enclosing the carbonizing chambers, a burner located at the foot of each branch of each flue and having gas and air openings; a gas supply conduit individual to each burner, a tube leading to each gas conduit and provided with a regulating valve, an end pipe on which said tubes are branched provided with a regulating valve, and a main gas conduit whereon said end pipe is mounted; a plurality of air conduits individual to each burner and leading to the same for supplying heated air thereto, an air chamber from which the air conduits lead, means for regulating the air supplied by each air conduit, and an intermediate heating flue in port communication with the air chamber, a collector chamber communicating with said intermediate flue, and a regenerating chamber communicating with said collector chamber; whereby each flue can be individually heated, independently of the others, to the desired temperature by combustion of gas admitted in the desired quantity and burned with the proper proportion of air.

In testimony whereof I have signed this specification in the presence of two subscribing witnesses.

ERNEST ORÉ.
